UNITED STATES PATENT OFFICE.

GEORG ULLRICH, OF MAGDEBURG, GERMANY, ASSIGNOR, BY MESNE ASSIGNMENTS, TO THE CHEMICAL FOUNDATION INC., A CORPORATION OF DELAWARE.

MAGNETIC SEPARATOR.

1,404,074.

Specification of Letters Patent. Patented Jan. 17, 1922.

Application filed October 8, 1914. Serial No. 865,707.

(GRANTED UNDER THE PROVISIONS OF THE ACT OF MARCH 3, 1921, 41 STAT. L, 1313.)

To all whom it may concern:

Be it known that I, GEORG ULLRICH, engineer, subject of the King of Bavaria, residing at Magdeburg, Germany, have invented 5 certain new and useful Improvements in or Relating to Magnetic Separators, for which I have filed application in Germany Oct. 20, 1913, in Holland Sept. 4, 1914, and Austria Sept. 4, 1914, and of which the following is 10 a specification.

This invention relates to magnetic separators in which the material to be treated is conducted through the field gap formed between the magnet and the pole situated 15 above it. In the known separators of this kind the conducting of the material to be treated is carried out in different ways. For instance, in my U. S. Patent No. 1,046,685 it consists of a continuous conveying belt 20 which runs over two rollers. At the middle, however, the upper and lower parts of the belt are brought together by means of guiding rollers, and these two contacting parts of the belt are situated in the field gap of the 25 magnet. Considerable disadvantages are caused by the running of a so-constructed separator, the driving rollers and the two parts of the belt running in opposite direction consume considerable force, the belt 30 will soon be worn out, and above all, the important magnetic force is considerably weakened by the double thickness of the belt, and the consequent necessary enlargement of the field gap.

35 In case the construction of the separator permits it, the lower part of the belt is carried around the lower magnet as is the case in the British Patent No. 20,545 of 1906. The disadvantage caused by this, is that the 40 machine has to be made comparatively large, because the belt rollers must be given a greater diameter than the height of the magnet pole. The carrying of the belt around, is, however, not always possible. 45 The cited British patent shows, furthermore, a device for carrying away the magnetically separated material, which comprises a drum, a body situated in the field gap and a second magnetic body situated thereabove. The 50 two magnet poles in this case constitute each a separate magnetic body. They are in no way connected, and the two magnetic bodies are, indeed, so far separated from each other

that the drum is able to rotate between them. When the upper magnet also excites the intermediate body, the lower magnet and its body still constitute two completely separated members. This separation has, however, the great disadvantage that the conductor of the lines of force becomes interrupted, and that the magnetic force corresponding to the useful electric energy, can only partly come into operation in the field gap. In any case, it will be considerably weakened. In accordance with this British 55 patent, there is created between the upper magnet and the intermediary body, another field gap, which by means of its magnetic influence on the conveying means, considerably retards the conveying movement. 60

All the enumerated disadvantages which are to be found in known magnetic separators, are avoided in the present invention, which, moreover, makes it possible, by utilizing the same electrical and mechanical 65 power, to make a machine of considerably smaller dimensions, which, nevertheless, produces a separating action of a strength 70 which has hitherto been considered unattainable.

75 For this purpose, the magnetic member conducting the lines of force is provided with a window or passage, which has less width than the magnetic member itself, so that on one or both sides of the window or 80 the passage, the iron of the magnetic member is left intact. The lines of force intended for operating the field gap are now conducted past the passages through this magnetic iron remaining on one or both sides 85 of the passage. These lines of force will therefore not be interrupted and are able to operate with undiminished strength in the separating field gap, as the conveying portion 90 of the belt for the material to be separated, is carried to the operating field gap, and the return portion of the belt through the passage of the magnet. The conducting rollers 95 of the belt, as well as the entire machine, can consequently be constructed considerably 100 smaller.

105 A means for carrying the invention into effect is shown in the drawing. Fig. 1 shows a vertical section in the direction of the movement of the band, Fig. 2 shows a section across the direction of movement of the

conveying band; "a" is an upper pole or magnetic discharging body of any kind. The material to be treated is conducted above the lower pole "f" by means of the band "e" running over the rollers "c," "d." The returning part of the band runs through a window or rectangular passage *g* in the lower pole, which window may be arranged either above or below the exciting coil. The 10 coil *h* may also be placed partly above and partly below the passage.

What I do claim as my invention and wish to secure by Letters Patent, is:

1. A magnetic separator having a magnetic body conducting the lines of force, an opposing pole forming a field gap with said magnetic body, said magnetic body being provided with a passage which has less width than the magnetic body, leaving magnetizable material extending past said passage in order not to interrupt the lines of force intended for the field gap, a suitably guided conveying belt for the material to be treated, one portion of said belt passing through the 20 field gap and another portion of the belt passing through said passage.

2. A magnetic separator having a magnetic body conducting the lines of force and constituting the lower pole, an opposing pole 30 forming a field gap with said magnetic body,

said magnetic body being provided with a passage through said lower pole leaving magnetizable material extending past said passage, a suitably guided conveying belt for the material to be treated, one portion of said belt passing through the field gap and another portion of said belt passing through said passage, said passage being situated adjacent to said coil. 35

3. A magnetic separator having a magnetic body conducting the lines of force and constituting the lower pole, an opposing pole forming the field gap with said magnetic body, said magnetic body being provided with a passage through said lower pole leaving magnetizable material extending past said passage, a suitably guided conveying belt for the material to be treated, one portion of said belt passing through the field gap and another portion of the belt passing 40 through said passage, one part of said coil being situated above and another part below said passage. 45

In testimony whereof the foregoing specification is signed in the presence of two witnesses. 50 55

GEORG ULLRICH.
